UNITED STATES PATENT OFFICE.

SAMUEL K. SMITH, OF NEW BRIGHTON, PENNSYLVANIA.

KILN FOR BURNING BRICK, POTTERY, &c.

SPECIFICATION forming part of Letters Patent No. 517,893, dated April 10, 1894.

Application filed September 14, 1893. Serial No. 485,526. (No model.)

To all whom it may concern:

Be it known that I, SAMUEL K. SMITH, a citizen of the United States, residing at New Brighton, in the county of Beaver and State 5 of Pennsylvania, have invented certain new and useful Improvements in Kilns for Burning Brick, Pottery, &c.; and I do hereby declare the following to be a full, clear, and exact description of the invention, such as will 10 enable others skilled in the art to which it appertains to make and use the same, reference being had to the accompanying drawings, and to the letters and figures of reference marked thereon, which form a part of this specification.

15 My invention relates to improvements in pottery or brick kilns and consists in the construction of the foundation of such kilns with a central quadrangular flue system, of equal 20 sectional area with the main connecting flue which is built diametrically across the foundation, said central flue system opening into said main flue on both sides and providing greater outlet area for the gases, and, consequently, 25 greater uniformity of temperature; in the radial system of flues extending from said central flues to the outer wall of the kiln and connected by "ports" or openings which permit the free passage of gases of 30 combustion from one to the others, whereby the construction of this portion of the kiln is lighter and stronger than in the usual method of building; expansion and contraction of flue walls is better provided for 35 and the kiln more quickly and uniformly heated or cooled than by any other known method of building; in the construction of such radial flues, with the alternate flues opening, at their inner ends, into the central 40 flue system, and at their outer ends, into the uptake flues within the kiln wall, and the other, adjoining radial flues, with their inner ends closed and their outer ends opening through the kiln walls and fitted as fire holes, 45 whereby the structure may be fired, as an up-draft kiln, from below the floor. In the construction, upon the described central and radial flues, of a series of parallel flues connected by "ports" with all the radial flues 50 over which they pass, and supporting a floor which is "ported" over each of said parallel

flues, whereby a continuous passage is formed for flame or combusting gases, either from above, within the kiln to the lower radial flues and their connecting uptake flues, or, 55 from the lower flues upward through the body of the kiln to the upper outlet flues, whereby the kiln may be used as an "updraft" kiln to dry the ware and its course reversed and fired as a "downdraft" kiln to vitrify the ware. 60

In the accompanying drawings Figure 1 is an elevation of such a kiln as my invention relates to. Fig. 2 is a vertical transverse section of such a kiln, upon the line G H, Fig. 4. Fig. 3 is a vertical transverse section upon 65 the line I K, Fig. 4. Fig. 4 is a horizontal section upon the lines A, B, C, D, and E, F, Fig. 2, and Fig. 5 is a vertical longitudinal section through two such kilns and their connecting flue 1.

I build, of brick, upon a proper foundation, a connecting flue 1, which passes diametrically across the kiln, passing through the outer wall 11, and connects with similar kilns upon one or both sides; centrally, within the floor 75 area of the kiln, and occupying about one-fifth of said floor area, I construct a square flue system 2, 2, of the same sectional area as the connecting flue 1, two of its sides being parallel with said connecting flue and the other two sides opening therein; radial walls are built from this central flue 2 to the outer wall 11; of the flues formed by these radial walls, each alternate flue, from the transverse connecting flue 1, is extended into the central flue 2, 2, 80 at its inner end, and is connected with an "uptake flue" 13, in the wall 11, at its outer end as shown at 3, 3, Fig. 4, while the adjoining flues, as 4, 4, are closed at their inner ends and have their outer ends extended through 85 the kiln wall 11, to form fire holes, which are fitted with doors 20, 31. Each of the radial flues thus formed is connected with its neighboring flues by the openings or "ports" 16, 16, in section A B, Fig. 4. Upon the system 90 of flues, thus formed, a series of parallel walls 18, 18, is built to extend over the entire floor area of the kiln, and the spaces between said walls form a second series of flues 7, 7, section C, D, connected with the underlying flues 100 over which they pass by the openings 15, 15; upon the walls 18, 18, the floor of the kiln is

laid, as at section E F, Fig. 4, and a series of openings 9, 9, connect the parallel flues 7, 7, with the interior of the kiln.

Immediately above the flues 4, 4, the furnace "bags" 10, 10, are built, connecting with the outer wall 11, and extending into the interior of the kiln; the fire holes 6, of these furnaces 10 are fitted with grate bars and outer fire doors 19, and all ash pits are also fitted with doors 19^a for closing to prevent inflow of air. The "uptake" flues 13, are fitted, at about the upper fire level, with dampers 14, and the connecting flue 1 is fitted with a damper 27, at a point outside the wall 11.

15 Immediately above the "furnace bags" 10, 10 flues 25, 25, are carried up through the wall 11, and are each provided with a cover damper 26, 26, Fig. 2; chimneys 24, 24, to extend the flues 13, 13 are built upon the outer wall 11, 20 and similar chimneys may, if desired, extend the flues 25, 25, to any desired height.

In operation, a kiln of my invention, is filled with brick or "ware" through the door 30, which is then bricked up. The damper 27 in 25 the connecting flue 1 is closed; the uptake flues 13, 13 are also closed by means of their dampers 14, 14, and the cover dampers 26 upon the upper flues 25 are opened; fires are kindled in the lower fire holes 5, 5, of the flues 30 4, 4, and the doors of the upper furnaces are tightly closed. The heat from the fires in 5, 5, is distributed through the lower system of flues by the "ports" or openings 16, 16, rises through the ports 15 15 into the parallel flues 35 7, 7, and passes into the body of the kiln through the floor ports 9, 9, thence it arises through the ware or bricks and is borne out through the open upper flues 25, 25; by this method the ware is quickly dried, the steam 40 from the ware is carried off upward with the escaping gases, and the lower layers of "ware" are not softened or crushed, as is often the case from the excessive moisture in "drying off" by down draft. When the ware is dry, 45 fires are kindled in the upper fire holes 6, 6, the dampers 14, 14, in the uptake flues 13, 13, are opened and the damper covers 26 on the flues 25, are closed; at the same time the fire doors 20 and the ash pit doors 31, of the lower 50 fire holes 5, are closed, and the burning gases from the fires 6 pass over the bags 10, through the ware and down through the floor "ports" 9, 9, to the parallel flues 7, whence they pass through the radial flues 3, 3, to the uptake flues 13. Ordinarily, the heat is very evenly 55 distributed all over the contents of the kiln, because of the perfect distribution of draft through the floor ports 9, 9, and the equality of the draft from below the floor 8 to the flues 13, but if, for any reason, it is desired 60 to retard the heating in one portion of the kiln, the damper 14, in the flue 13, nearest that portion is closed and the doors 20, 31 of the fire-hole 5, nearest that portion, are 65 opened; there is a retardation of circulation of the hot gases caused by closing the damper, and an influx of cool air from the open doors

and by this means the heating is kept uniformly even and under control. When the kiln has been properly "burned" the damper 7c 27 is raised and all doors and dampers are opened. Cool air from the lower fire-holes 5, 5, passes into the flues below the floor and the heated air is carried off through the uptake flues 13 and 25. 75

Referring to Fig. 5, which illustrates the process of firing a series of my kilns, I represents a kiln in which the ware has been dried, or "green fired" by the "updraft" portion of the process, and in which the fires 80 have been started in the furnace bags 10, 10, and the dampers 25^a of the uptake flues 25 closed. K represents an adjoining kiln which has been filled with "green" or damp ware and sealed up, and in which, the dampers 26 85 are opened and all others closed. The dampers 27^a, 27^b in the main flue 1, between I and K are opened and the products of combustion, in the furnace bags 10, of kiln I pass down through the ware in I, and, by the flue 90 1, to the "green" ware in K through which they pass off by the flues 25. When the ware in K is sufficiently fired to enable the operative to continue the burning by the down-draft process, the products of combustion are 95 shifted, in their course, by means of the valves 27, to another kiln and the fires in the furnace bags 10, of the kiln K are lighted and that kiln fired in the usual manner of down draft kilns. By this process of firing a saving of at least twenty per cent. of fuel is attained and a better quality of ware results 100 from the more uniform quality of the updraft drying or "green firing" of the ware by means of the gases from the down draft firing of the 105 adjoining kiln. It will be seen that this form of construction enables the operative to "burn a kiln" quickly because of the rapid "drying out;" it gives economy in "ware" because 110 the ware is not subject to steaming or crushing from the down draft drying; it is more quickly cooled and emptied because of the admission of cool air below the floor; and it is less liable than ordinary kilns to destruction of its flues from expansion and contraction because of the greater surface and stell 115 lar form of said flues.

I claim as my invention—

1. In a kiln for brick or pottery, a foundation flue system consisting of a central quadrangular flue of like section with the equatorial connecting flue and having two of its sides parallel therewith and the other two sides opening therein; a series of radial flues, opening, at their inner ends, into said quadrangular flue and, at their outer ends into damper controlled "uptake" flues in the wall of the kiln, a second series of radial flues, interposed between said open end flues, and closed at their inner ends, but with their outer 125 ends passing through the kiln wall, fitted as "fire-holes" and provided with tight doors; "ports" or openings connecting said radial flues each with the others; a series of paral 130

lel flues built upon and connecting with said radial and quadrangular flues, and a "ported" or perforated floor superposed upon said parallel flues, whereby, when "fired" in the 5 "fire-holes" of the radial flues, the products of combustion are distributed evenly over the entire floor space and arise within the kiln as shown and described.

2. In a reversible draft kiln, the combination, with a series of lower fire holes connected by radial flues with a main equatorial flue and with rectangular flues opening into said main flue, a series of parallel flues superposed upon said radial flues and main flue and a kiln 10 floor laid upon said parallel flues, openings or ports through said floor to said parallel flues, and openings or ports connecting said parallel flues with the underlying radial flues, rectangular flue and main flue, damper controlled 15 uptake flues connected with said radial flues, furnace bags built over said lower fire holes, and fitted with tight doors, a series of damper controlled outlet flues, opening, within the kiln, above said furnace bags and 20 passing out through the top of the kiln wall and dampers within the main flue, outside the kiln walls, whereby the combusting gases from said furnace bags may be directed downward through the floor and thence upward 25 through the uptake flues, or to be carried away through the main flue or gases, from the lower fire holes, may be carried upward 30

through the floor and escape through the upper series of outlet flues, as shown and described.

35

3. In a kiln of the described class the combination, with a central quadrangular distributing flue and an equatorial main connecting flue, each opening into the other, of a series of radial flues opening into the central quadrangular flue and into damper controlled uptake flues; a series of "fire-hole" flues having outer doors and connecting with their neighboring radial flues by "ports" or openings; a series of parallel flues upon 40 and connecting with said radial flues; a perforated floor upon said parallel flues, and a series of "furnace bags," above the fire hole flues, fitted with tight doors, and a series of damper controlled outlet flues above said 45 "furnace bags" and within the kiln wall, whereby the kiln may be fired as an updraft kiln until the ware is dried and subsequently as a downdraft kiln until the ware is wholly 50 burned or vitrified, and, thereafter may be quickly cooled by the opening of the flues and doors, as shown and described.

In testimony whereof I affix my signature in presence of two witnesses.

SAMUEL K. SMITH.
